UNITED STATES PATENT OFFICE.

TRUMAN P. HOPKINS, OF MILWAUKEE, WISCONSIN.

CURTAIN-FIXTURE.

SPECIFICATION forming part of Letters Patent No. 259,156, dated June 6, 1882.

Application filed May 3, 1881. (No model.)

To all whom it may concern:

Be it known that I, TRUMAN PRESCOTT HOPKINS, of Milwaukee, in the county of Milwaukee, and in the State of Wisconsin, have invented certain new and useful Improvements in Curtain-Fixtures; and I do hereby declare that the following is a full, clear, and exact description thereof.

My invention relates to certain new and useful improvements in curtain-fixture, all as more fully set forth hereinafter.

In the drawings, Figure 1 is a perspective view of my improved curtain-fixture. Fig. 2 is a perspective view of a portion thereof on an enlarged scale; and Fig. 3 is a similar view of the whole, also on an enlarged scale.

A represents a plate or surface of wood, into which the ends of the brackets B B' are securely driven. In practice I usually omit this plate and drive the said brackets directly into the upper part of the window-frame; but I may use a plate if more convenient.

C is the top slat of the shade, to which the shade D is secured in the usual manner, its lower end being secured around the roller E also, as usual. Each bracket is provided in its bent outer end with an eye, b and b', respectively, and is perforated with three holes, c, c', and c'', through which the cords F F' and I I' pass, 30 their outer ends terminating in the tassels G and G'. The inner ends of the cords F and F' are secured at f and f'', respectively, to the upper ends of the slat C, while the inner ends of the cords I and I' are secured to the ends of the roller E, all as set forth more fully hereinafter.

The operation of my device is extremely simple, but very effective. For instance, supposing that the shade is in the position shown in Fig. 1. Should it be desired to lower the shade from the top without disturbing the position of the roller E, it is only necessary to gently ease up on the left-hand tassel, G; the lengthening of the cord occasioned by the operation serving to revolve the roller E, (without otherwise changing its position,) and thus keeping the shade taut, while by pulling on the said tassel G the upper portion of the shade may be raised to any height desired without disturbing the position of the roller. Correspondingly, the shade may be raised or lowered from the bottom without disturbing the position of the slat

C by pulling or easing up on the right-hand tassel, G', at will. The whole shade may be raised or lowered without disturbing the relative positions of the slat and roller (previously 55 adjusted to expose any length of shade desired) by gently pulling on or easing both tassels simultaneously, one being held in each hand.

The drawings clearly show in Fig. 3 the manner in which the cords are passed through the several perforations and eyes of the brackets and secured to the frame of the shade. Beginning with the left-hand tassel, G, two cords, F and F', are carried up through the eye b of bracket B, and the cord F is carried along the outside of said bracket and through its farthest 65 perforation, c, and thence brought down and secured to the upper left-hand corner of the slat C at f. The other cord, F', is carried in like manner through the eye b' and along the outside of the bracket B, through the middle perforation, c', and across to the other bracket, B', through the perforation c in that bracket, and down to the slat C, being secured to its upper right-hand corner at f''. Thus the two cords 70 F and F' from the left-hand tassel, G, operate the shade from the top thereof, as described. The two cords I and I' from the right-hand tassel, G', are carried in like manner through the eye b' of the bracket B' and along its outer 75 side, the cord I passing through the middle perforation, c', of said bracket B', and then across to the bracket B, and through the first perforation, c'', therein, and then down and around the shank h of the button H, at which 80 point it is secured to the left-hand end of the roller E. The cord I', after passing through the eye b' of bracket B', along the outside of said bracket, and through its first perforation, c'', is brought down and wound around the shank h' of 85 the button H', and there secured to the right-hand end of the roller E, so that the two cords I and I' from the right-hand tassel, G', serve to operate the shade from the bottom, as hereinbefore set forth.

The tassels are weighted in order to serve as counter-balances to the weight of the shade and assist in keeping the latter in any position to which it may be adjusted.

The roller E is provided at each end with 90 buttons H H', around the shanks h h' of which the ends of the cords are wound once or twice

before being secured to the said rollers, where they are driven in by the said shanks or otherwise fastened. Should the roller at any time hang unevenly, it is only necessary to wind or unwind the cord once or twice on the said shank *h* or *h'* in order to instantly remedy this defect.

5 My improved curtain-fixture is simple in construction and not liable to get out of order, as is the case where springs are employed to assist in raising or lowering the shade, and, as shown, can at any time be rendered true and even in its operation, where it has sagged out of position, by winding or unwinding one or more loops of the cord around the shank of one 10 of the buttons, even when it has been unevenly or inartistically adjusted to the window-frame.

15 The effective operation of this device is not dependent entirely upon the exact counterbalancing of the shade and weighted tassels; but it will work equally well even though there is a disproportion of weight between them by reason of the brackets *B* and *B'* being constructed with their outer ends (which form the eyes *b* and *b'*) bent at an angle to the main portion of 20 the said brackets, whereby the cords, after passing through the perforations in the shanks of the brackets, turn at almost a right angle, so that a very light weight at the ends of the said cords will cause them to impinge against the 25 edges of the said eyes, and by this frictional contact aid in supporting the shade at any height desired.

30 I am aware that I am not the first to have

arranged cords for supporting a curtain in adjustment in perforated brackets, so that the 35 friction of the cords in the perforations, aided by the weight of the tassels at the ends of the cords, afforded sufficient resistance to support the weight of the curtain and secure the curtain when adjusted either from top or bottom, 40 as such construction may be found in the patents of Cornell, dated August 1, 1876, and January 1, 1878, respectively, and such I do not claim broadly.

Having thus described my invention, what 45 I claim as new, and desire to secure by Letters Patent, is—

1. In a curtain-fixture, the brackets *B B'*, having bent outer ends provided with eyes *b b'*, and each bracket having three smaller perforations, 50 *c, c', and c''*, formed therein, as set forth.

2. In a curtain-fixture, the combination of the brackets *B B'*, each having bent ends, with eyes *b* and *b'* respectively formed therein, and three smaller perforations, *c, c', and c''*, with the 5 described system of cords *F F'* and *I I'*, the tassels *G G'*, and a window-shade formed with top slat and bottom roller and buttons, all substantially as set forth.

In testimony that I claim the foregoing I 60 have hereunto set my hand this 28th day of February, 1881.

TRUMAN P. HOPKINS.
